US0D1061745S

(12) **United States Design Patent** (10) Patent No.: **US D1,061,745 S**
(45) Date of Patent: ** Feb. 11, 2025

(54) **TOY**

(71) Applicant: **Alex Hochstrasser**, Zürich (CH)

(72) Inventor: **Alex Hochstrasser**, Zürich (CH)

(**) Term: **15 Years**

(21) Appl. No.: **35/520,647**

(22) Filed: **Jan. 20, 2024**

(80) **Hague Agreement Data**

Int. Filing Date: **Jan. 20, 2024**

Int. Reg. No.: **DM/235297**

Int. Reg. Date: **Jan. 20, 2024**

Int. Reg. Pub. Date: **Apr. 26, 2024**

(51) LOC (15) Cl. 21-01

(52) U.S. Cl.

USPC **D21/621**

(58) **Field of Classification Search**

USPC D21/490, 576, 96, 598, 599, 602, 611,
D21/618-621, 661, 653, 656, 658
